SYLVAN N. LEVY, OF WILMINGTON, DELAWARE

MEANS FOR FORMING STAR DRILLS

Application filed December 24, 1927. Serial No. 242,396.

This invention relates to forging apparatus, the particular adaptation illustrated being a device for forming star drills or similar fluted products, and the object of the invention being to increase production over the methods now employed in the manufacture of this class of merchandise.

The details of the device will be fully disclosed hereinafter, reference being had to the accompanying drawings, of which:

Fig. 1 is a sectional elevation of the device taken on the line 1—1 of Fig. 3;

Fig. 2 is a sectional elevation taken on the line 2—2 of Fig. 3;

Fig. 3 is a sectional plan view taken on the line 3—3 of Fig. 2;

Fig. 4, 5 and 6 are respectively a plan, side and front elevation of one of the forming dies;

Figs. 7 and 8 are respectively a plan and side elevation of one-half of the die holder;

Figs. 9 and 10 are respectively a plan and side elevation of one-half of the work holder, and

Figs. 11 and 12 are respectively a plan and side elevation of a finished drill.

Referring to Figs. 1, 2 and 3 of the drawings, the device comprises a base plate 1 having a vertically extending ring 2 secured thereto by means of screws 3. Within the ring 2 is a die holder 4, and within the die holder 4 is a work holder 5. Slidably mounted in the die holder 4 and the work holder 5 is a series of dies 6, in the present instance four in number, arranged in pairs. The respective dies of each pair are arranged for movement in opposed relation to each other and the different pairs are arranged at right angles with respect to each other, as shown in Fig. 3. The dies 6, 6 are all adapted for movement radially toward and from a common center.

Each of the die members 6 comprises a body portion 7, adapted to slide in a groove 8 formed in the die holder 4, and a reduced blade portion 9 adapted to slide in a groove 10 formed in the work holder 5. The front edge 11 of each of the blades 9 is beveled adjacent the top edge 12 of the blade, as indicated at 13 (Figs. 4, 5 and 6), said bevel tap-

ering in all directions from the said top edge 12 of the blade to a common point 14 at the bottom edge 15 of the blade, see Fig. 6. The rear or outer edge of each of the dies 6 is inclined as illustrated at 16, for purposes hereinafter set forth.

The die holder 4 and the work holder 5 respectively are split along a common line 2—2, Fig. 3, which divides these elements into separate halves 4a, 4a and 5a, 5a respectively.

The half sections 4a, 4a of the die holder 4 are each provided with a tongue 20 adapted to slide in guide openings 21, 21 formed in the respective sides of the base ring 2. Guide blocks 22, 22 are carried by the said base ring 2, and engage flat faces 23, 23 formed on the opposite sides of the die holder 4 parallel to the tongues 21.

Behind and in radial alignment with each of the die members 6, the ring 2 is provided with a vertically extending groove 24. These grooves 24 are substantially the same width as the tongues 21 as seen in Fig. 3. The guide blocks 22, 22 are secured in the grooves 24a which occupy positions at right angles to the grooves 24 located above said tongues.

In each of the said grooves 24 located above the tongues 21 is operably mounted a double wedge element 25. Each of these double wedge elements 25 includes a central portion 26 having an inclined face 27 which is adapted to cooperate with the inclined face 16 on the die members 6, situated adjacent said tongues 21. At either side of the central portion 26 is a lateral vertically extending flange 28, provided at the lower end with an inclined face 29 which is adapted to cooperate with a rounded corner 30 on the upper rear edge of the respective half 4a of the die holder 4.

The wedge elements 25, 25 extend from side to side within the grooves 24, 24 which are above the tongues 21, 21 respectively while the grooves 24a, lying at right angles to the tongues 21, are occupied in part by the guide blocks 22, 22.

Between the guide blocks 22, 22 in each groove 24a is operably mounted a wedge element 25a having an inclined face 27a which

cooperates with the die members 6, 6 which are aligned with the grooves 24a, 24a.

The wedge elements 25, 25 and 25a, 25a are each provided with a threaded shank 35 extending above the upper surface 34 of the said wedge element. The shank 35 of each of the wedge elements passes through an aperture 36 formed in the bottom wall 37 of a cup-shaped element 38. The cup-shaped element 38 has a threaded cavity 39 in which is located a nut 40, which engages the threads of the cavity 39, whereby the said nut 40 may be jammed down tight against the bottom wall 37 of the cup element 38. The nut 40 is also provided with a threaded aperture 41 for the reception of the threads 42 on the wedge shank 35. By this means the cup-shaped elements 38, 38 and the wedge elements 25, 25a are rigidly though removably held together, the cup-shaped element 38 acting as a head for the wedge 25.

The threads in the cavity 39 of the head 38 are adapted to receive a threaded stud 43 which is riveted to a plate 45, and a lock nut 44 is provided on the stud 43 between the head 38 and the plate 45. This construction provides for the removal of the wedge elements 25 from the plate 45, in case of necessity, and also provides adjustment for said wedge elements in order that the inclined faces thereof may be properly aligned with the inclined faces 16 of the die members 6 and with the respective halves of the die holder 4.

35 In operation the base plate 1 is secured to the stationary bed of a punching or stamping machine, and the plate 45 which acts as a common carrier for said wedge members is secured to the movable head of the machine (not shown), said plate 45 being provided with a spindle 46 by means of which said connection may be effected.

The base plate 1 is provided with a centrally located opening 47 which is in axial alignment with a cavity 48 formed in the work holder 5. A work receiving opening 50 is provided in the work holder 5 and extends from the cavity 48 therein to the top of the said work holder, and is axially aligned with the common center from which the die members 6, 6 radiate.

Assuming that the movable head of the machine is raised to such a position that the points 51 of the wedge members 25, 25a are adjacent the top face of the base ring 2, a preheated blank, consisting of a suitable length of tool steel, is inserted from underneath, through the opening 47 in the base plate 1, through the cavity 48 formed in the work holder 5 and into the work receiving opening 50 therein until the upper end of the said blank is substantially flush with the upper edges 12 of the die members 6. Insertion of the blank causes the die members 6, 6 to be moved radially outward by the up-

per end of the blank engaging the tapering front edges 11 of the die blades 9.

After the blank is inserted, the movable head of the machine is moved downwardly, the wedge members 25, 25a enter the grooves 24, 24a in the base ring 2 behind the die members 6, 6 and the respective halves 4a, 4a of the die carrier 4. As the movable head of the machine descends the inclined faces 29, 29 of the wedges 25, 25 engage the rounded edges 30, 30 of the respective halves 4a, 4a of the die holder 4, causing the two said halves to move toward each other, consequently causing the two halves 5a, 5a of the work holder 5 to move toward each other until the blank is gripped tightly within the work receiving opening 50 of the said work holder 5.

Continued downward movement of the wedges 25, 25 causes the inclined faces 27, 27 thereof to engage the inclined faces 16, 16 of the die members 6, 6. At the same time the inclined faces 27a, 27a of the wedge 25a, 25a engage the inclined faces 16, 16 of the die members 6, 6 with which they cooperate. As the wedges 25, 25a continue their downward movement, the die members 6, 6 are synchronously moved toward the above mentioned common center and the beveled edges 11, 11 of the respective die blades 9 are forced into the heated blank, to the position illustrated in Fig. 3, thereby making the indentations illustrated at x^1 in the blank x , which produces fins x^2 , x^2 disposed at right angles to each other. The fins x^2 , x^2 are later ground as illustrated at x^3 , x^3 Figs. 11 and 12 to complete the star drill.

After the blank has been formed, the direction of movement of the movable head of the machine is reversed and the wedges 25, 25a are thereby moved upwardly in the grooves 24, 24a, and by a slight lateral movement of the completed blank the die members 6, 6 and the halves 5a, 5a of the work holder 5 are moved sufficiently to loosen the blank relative to these members, after which the blank is withdrawn from underneath and a new blank inserted as above noted, after which the cycle of operations is repeated.

While the drawings illustrate a device for forming star drills, it will be obvious to those familiar with the forging art that the device may be used in the formation of any other form of fluted forged product, and while there are four dies illustrated in the drawings any desired number of dies may be employed; also the die holder and work holder may be split into as many individual parts as may be deemed necessary for a given article and a given number of dies.

The bore of the work holder is finished to agree with the diameter of the finished product, thereby obviating the necessity of grinding the article to a finished diameter after the forging thereof is completed.

I claim:

1. The combination in a device for forging fluted articles of a plurality of die members adapted for movement radially with respect to a common center, and a work holder comprising a plurality of relatively movable sections surrounding said center for positioning a blank in coaxial alignment with said center, said work holder having guideways formed therein for radially guiding said die members relative to said center.

2. The combination in a device for forging fluted articles of a plurality of die members adapted for movement radially with respect to a common center, and a work holder comprising a plurality of relatively movable sections surrounding said center for positioning a blank in coaxial alignment with said center, said work holder having guideways formed therein for radially guiding said die members relative to said center and means for synchronously moving said die members toward said common center and into said blank.

3. The combination in a device for forging fluted articles of a plurality of die members adapted for movement radially with respect to a common center, a die holder for said dies, a work holder comprising a plurality of relatively movable sections surrounding said center for positioning and holding a blank in coaxial alignment with said center, and guides formed in said die holder and said work holder for said die members.

4. The combination in a device for forging fluted articles of a plurality of die members adapted for movement radially with respect to a common center, a die holder for said dies, a work holder comprising a plurality of relatively movable sections surrounding said center for positioning and holding a blank in coaxial alignment with said center, guides formed in said die holder and said work holder for said die members, and means for synchronously moving said die members toward said common center and into said blank.

5. In a device for forging fluted articles, the combination of a base element, a plurality of die members adapted for movement radially with respect to a common center, a holder for said die members located within said base element, a work holder comprising a plurality of relatively movable sections surrounding said center for positioning and holding a blank in coaxial alignment with said common center, guideways formed in said die holder and said work holder for said die members, and wedge members operable between said die members and said base element for moving said die members toward said common center and into said blank.

6. In a device for forging fluted articles, the combination of a base element, a plurality of die members adapted for movement

radially with respect to a common center, a holder for said die members located within said base element, a work holder comprising a plurality of relatively movable sections surrounding said center for positioning and holding a blank in coaxial alignment with said common center, guideways formed in said die holder and said work holder for said die members, wedge members operable between said die members and said base element for moving said die members toward said common center and into said blank, and means for synchronously moving said wedge members for effecting a synchronized movement of said die members.

7. In a device for forging fluted articles, the combination of a base element, a plurality of die members adapted for movement radially with respect to a common center, a holder for said die members located within said base element, a work holder comprising a plurality of relatively movable sections surrounding said center for positioning and holding a blank in coaxial alignment with said common center, guideways formed in said die holder and said work holder for said die members, wedge members operable between said die members and said base element for moving said die members toward said common center and into said blank, means for synchronously moving said wedge members for effecting a synchronized movement of said die members, and guideways formed in said base element for said wedge members.

8. In a device for forging fluted articles, the combination of a base element, a plurality of die members adapted for movement radially with respect to a common center, a holder for said die members comprising a plurality of separate elements slidably mounted within said base element, a work holder comprising a plurality of separate elements respectively located within the said separate elements of said guide holder, guideways formed in said die holder and said work holder for said die elements, means for moving the respective elements of said die holder and said work holder to clamp a blank in position in axial alignment with said center, and means for moving said die members relative to said die holder and said work holder to engage the blank.

9. In a device for forging fluted articles, the combination of a base element, a plurality of die members adapted for movement radially with respect to a common center, a holder for said die members comprising a plurality of separate elements slidably mounted within said base element, a work holder comprising a plurality of separate elements respectively located within the said separate elements of said die holder, guideways formed in said die holder and said work holder for said die elements, means for moving the respective elements of said die holder and said work holder

to clamp a blank in position in axial alignment with said center, means for moving said die members relative to said die holder and said work holder to engage the blank, and means for guiding the respective elements of said die holder in said base element.

10. In a device for forging fluted articles, the combination of a base element, a plurality of die members in said base element adapted for radial movement with respect to a common center, a holder for said die members comprising a plurality of separate elements slidably mounted in said base element for movement toward and from said center, a work holder comprising a plurality of separate elements respectively carried by the elements of said die holder, guideways formed in said die holder and said work holder elements for said die members, a series of wedge members having operating faces for operating the said die holder and work holder elements to grip a blank in coaxial alignment with said common center and having operating faces for operating a portion of the series of the said die members, and a second series of wedge members having operating faces for the remainder of die members.

11. In a device for forging fluted articles, the combination of a base element, a plurality of die members in said base element adapted for radial movement with respect to a common center, a holder for said die members comprising a plurality of separate elements slidably mounted in said base element for movement toward and from said center, a work holder comprising a plurality of separate elements respectively carried by the elements of said die holder, guideways formed in said die holder and said work holder elements for said die members, a series of wedge members having operating faces for operating the said die holder and work holder elements to grip a blank in coaxial alignment with said common center and operating faces for operating a portion of the series of the said die members, a second series of wedge members having operating faces for the remainder of die members, and a common carrier for all of said wedge members.

12. In a device for forging fluted articles, the combination of a plurality of die members adapted for movement radially with respect to a common center, means for positioning and maintaining a blank in coaxial alignment with said center, a plurality of wedge members for operating said die members and said blank maintaining means, a common carrier for said wedge members, and means for adjustably securing each of said wedge members to said common carrier comprising an externally threaded stud immovably secured to said common carrier, an internally threaded cup-shaped element adjustably mounted on said stud, a shank on said wedge member extending through an

aperture formed in the bottom of said cup element, a lock nut in the cup element between the bottom thereof and the end of the stud, said lock nut being threaded onto the end of the said wedge shank, and a lock nut on said stud between the common carrier and the cup element and adapted to engage the said cup element.

13. In a device for forging fluted articles, the combination of a plurality of die members each of which comprises a body portion and a blade portion, a holder for said die members comprising a plurality of individual elements having grooves for slidably receiving the body portions of said die members, a work holder comprising a plurality of individual elements having grooves for slidably receiving the said blade portions of said die members, said die holder elements, said work holder elements and said die members being adapted for movement radially with respect to a common center, a base element, means for guiding said die holder elements in said base element, means for guiding the die members in the die holder and work holder, wedge members operable between said base element and said die members and between the base element and the die holder elements, and guideways formed in said base element for said wedge elements.

14. In a device for forging fluted articles, the combination of a plurality of die members adapted for movement radially with respect to a common center, a work holder comprising a plurality of relatively movable sections surrounding said center for positioning a blank in coaxial alignment with said center, a holder for said die members, each die member comprising a body portion adapted to slide in a groove formed in said die holder and a blade portion adapted to slide in a groove formed in said work holder, each blade portion having a beveled edge adjacent said common center adapted to penetrate the side faces of said blank, and means for operating said die members.

15. In a device for forging fluted articles, the combination of a base element comprising a base plate and a base ring rigidly secured thereto, a plurality of die members adapted for radial movement with respect to a common center coincident with the center of said base ring, a split holder for said die members comprising a plurality of independent elements slidably mounted on said base plate within said base ring, a tongue on each of said elements adapted to slide in a groove formed in said base ring, a split work holder comprising a plurality of independent elements carried by the elements of said die holder respectively, wedges for operating said die holder and said work holding elements for gripping and maintaining a blank in coaxial alignment with the center of said base ring, wedges for operating said die members,

grooves formed in said base ring for guiding said wedges in operative alignment with the elements operated thereby, and a common carrier for said wedge adapted to synchronously move said wedges in said guide grooves.

5 16. In a device for forging fluted articles, the combination of a base element comprising a base plate and a base ring rigidly secured thereto, a plurality of die members adapted for radial movement with respect to a common center coincident with the center of said base ring, a split holder for said die members comprising a plurality of independent elements slidably mounted on said base plate within said base ring, a tongue on each of said elements adapted to slide in a groove formed in said base ring, a split work holder comprising a plurality of independent elements carried by the elements of said die holder respectively, wedges for operating said die holder and said work holding elements for gripping and maintaining a blank in coaxial alignment with the center of said base ring, wedges for operating said die members, 20 grooves formed in said base ring for guiding said wedges in operative alignment with the elements operated thereby, guide blocks located in the wedge guide grooves positioned adjacent the split in said die holder and adapted to be engaged by the sides of the respective elements of said die holder, and a common carrier for said wedges adapted to synchronously move said wedges in said guide grooves.

35 17. In a device for forging fluted articles, the combination of a base element comprising a base plate and a base ring rigidly secured thereto, a plurality of die members adapted for radial movement with respect to a common center coincident with the center of said base ring, a split holder for said die members comprising a plurality of independent elements slidably mounted on said base plate within said base ring, a tongue on each of said elements adapted to slide in a groove formed in said base ring, a split work holder comprising a plurality of independent elements carried by the elements of said die holder respectively, wedges for operating said die holder and said work holding elements for gripping and maintaining a blank in coaxial alignment with the center of said base ring, wedges for operating said die members, 40 grooves formed in said base ring for guiding said wedges in operative alignment with the elements operated thereby, guide blocks located in the wedge guide grooves positioned adjacent the split in said die holder and adapted to be engaged by the sides of the respective elements of said die holder, a common carrier for said wedges adapted to synchronously move said wedges in said guide grooves, and means for adjustably securing said wedges to said common carrier therefor.
